J. D. RENICK

GAS REGULATOR

Filed Sept. 14. 1923

Inventor
Joseph D. Renick

By C. Shepherd.

Attorney

UNITED STATES PATENT OFFICE.

JOSEPH D. RENICK, OF COLUMBUS, OHIO.

GAS REGULATOR.

Application filed September 14, 1923. Serial No. 662,654.

To all whom it may concern:

Be it known that I, JOSEPH D. RENICK, a citizen of the United States, residing at Columbus, in the county of Franklin and 5 State of Ohio, have invented certain new and useful Improvements in Gas Regulators, of which the following is a specification.

The present invention is directed to improvements in gas regulators.

The primary object of the invention is to provide a device of this character constructed in such manner that the flow of gas will be automatically regulated regardless of the 15 consumption, thereby eliminating the necessity of personal supervision.

With these and other objects in view, as will appear as the description proceeds, the invention consists in the novel features of 20 construction, combinations of elements and arrangements of parts, and hereinafter to be fully described and pointed out in the appended claims.

In the accompanying drawing:

25 Figure 1 is a vertical sectional view of the apparatus,

Figure 2 is a sectional view on line 2—2 of Figure 1, and

30 Figure 3 is a sectional view on the line 3—3 of Figure 1.

Referring to the drawing 1 designates the gas main in which is located the casing 2, said casing having valve seats 3 formed therein, the disk valves 4 which cooperate 35 with the seats being secured to a stem 5, the upper end of which is secured to a conventional form of diaphragm in the chamber 6, said chamber being in communication with the main 1 through a pipe 7. A standard 40 8 is supported by the casing 2 and holds the chamber 6 rigidly supported thereabove, said standard having a bracket 9 formed thereon, the purpose of which will appear later.

45 The regulator includes a tank 10 from the bottom of which extends a tubular casing 11 and enveloping said casing is a bell float 12. This float has a rod 13 carried thereby which is capable of sliding upwardly or downwardly in the top 14 of the tank 10, said top also having a vent 15 therein to permit any gas which might leak from the float to pass to atmosphere. A pipe structure 16 has one end connected to the main 1 and its other end supported by the top of the casing 11 and open-

ing into the bell float 12. The tank 10 is provided with a casing 17 in the sides of which are journaled the ends of a rock shaft 18 one end of which being provided with a crank 19 located exteriorly of said casing. The shaft 18 has one end of a bar 20 rigidly connected thereto, the other end of which being pivotally connected with a rod 13 by a clip 21, whereby said shaft will 65 be rocked as the bell float rises or falls under varying gas pressures.

Telescopically and adjustably connected with the crank 19 is a tubular arm 22 to the upper end of which is pivotally connected one end of a link 23, the other end of said link being pivotally connected with a clamp 24 adjustably mounted on the arm 25 which is fixed to one of the side frames 26 of the carriage 27. The carriage has 70 75 rotatably supported between its side frames 26 a pair of grooved wheels 28 which are adapted to travel upon the beam 29, said beam being pivotally connected intermediate its ends to the bracket 9 and having the 80 end adjacent said bracket slidably and pivotally connected with the stem 5, there being a stop 30 on said stem for engaging the beam when the stem moves downwardly. Supported by the ends of the frames 26 is 85 a bar 31 upon which is removably mounted weights 32.

Assuming that the parts are in the position as shown and the consumption of gas from the main is uniform, the carriage 27 90 will remain in a settled position. Now should the consumption be decreased gas under expansion from the pipe structure 16 will cause the bell float to rise and simultaneously therewith the shaft 18 will be rocked 95 through the medium of the bar 20 thus causing the arm 22 to swing in a direction to cause a link 23 to move the carriage 27 inwardly upon the beam, which action rocks said beam and permits the stem 5 to 100 move downwardly under the action of pressure in the chamber 6, thereby partially closing the valves 3 and consequently regulating the flow of gas into the main. It will be of course obvious that this operation is reversed when the consumption of 105 gas is increased. Owing to the presence of the weighted carriage the opening of the valves 3 will be positive, the carriage being susceptible to the varying pressures in 110 the system. It will be of course understood that the downward movement of the stem

5 is influenced by the pressure of the gases in the chamber 6.

Since the number of the weights 32 may be varied and the tubular arm 22 adjusted, as well as the link 23 with respect to the arm 25 it will be obvious that the apparatus can be conveniently adjusted to suit different pressure conditions and will operate without personal supervision.

10 What is claimed is:

1. In a gas regulator, a gas main, valves in the main, a stem for the valves, a tank having a bell float therein, a rod connected with the float, a beam pivotally connected 15 with the main and stem, a carriage slideable on the beam, an arm fixed to the carriage, and adjustable connecting means between the rod and beam for moving the carriage upon the beam upon the rise and fall of the bell float, as and for the purpose set forth.

2. In a gas regulator, a gas main including a casing, valves for controlling the flow of gas through the main, a stem for the

valves, a beam pivotally associated with the casing and stem, a carriage including 25 wheels for engaging the beam, weights removably mounted on the carriage, a tank having a bell float therein, and adjustable connections between the float and carriage for controlling the movement of the carriage upon the beam, as and for the purpose set forth.

3. In a gas regulator, a tank having a bell float therein, a casing carried by the tank and communicating therewith, a gas 35 main, valves for the main, a stem for the valves, a pivotally supported beam connected with the stem, a carriage on the beam, a rock shaft journaled in said casing, adjustable connections between the rock shaft and carriage, and means for connecting the rock shaft and bell float, as and for the purpose set forth.

In testimony whereof I affix my signature.

JOSEPH D. RENICK.
